BRAKING MECHANISM FOR COASTER WAGONS

Filed April 12, 1927

Inventor:

E.S. Showers

By Watson E. Coleman
Attorney

UNITED STATES PATENT OFFICE.

ERNEST S. SHOWERS, OF CHAMPION, MICHIGAN.

BRAKING MECHANISM FOR COASTER WAGONS.

Application filed April 12, 1927. Serial No. 183,109.

The object of this invention is to provide a 5
brake for coaster wagons, and particularly
to improve upon the construction illustrated
in my Patent #1,628,559, granted on the
10th day of May, 1927.

A particular object is to provide fixed 10
braking disks in connection with two rear
disk wheels, and provide means whereby the
rear disk wheels may be forced toward the
disks in order to put on the brakes, and pro-
vide means for urging the wheels away from
the disks when it is desired that the wagon
shall run free.

My invention is illustrated in the accom- 15
panying drawings wherein:—

Figure 1 is a longitudinal sectional view 20
of a wagon having braking mechanism
constructed in accordance with my invention.

Figure 2 is a rear elevation partly in sec- 25
tion of the wagon.

Figure 3 is a fragmentary bottom plan 30
view showing the brake guiding means.

Referring to these drawings, the wagon 35
platform 37 is supported on the front wheels
38 by means of a bolster member 39 support-
ing a bolster 40, this bolster being oscillat-
able by the steering mechanism, as for
instance, by means of the steering column 41.

Any suitable steering mechanism may be 40
used.

Between the platform 39 and the rear 45
axle sections and supporting the body from
the rear axle sections is a bolster 42, the
lower edge of which is grooved at 43 to re-
ceive the tubular rear axle sections 44. Through
each tubular member 44 is a rod 45, the inner 50
end of which is angularly bent and connected
to an operating member as will be later
stated. This rod extends through the 55
corresponding tube 44 and carries upon it a
cup-shaped cap 46 bearing against the
washer 47. This bears against a disk wheel
48 rotatably mounted upon the correspond-
ing tubular member 44. Mounted upon the 60
tubular member 44 inward of the disk wheel
48 is a support 49 carrying the annular
braking disk 50 adapted to bear against the
wheel 48 when the wheel is shifted and thus
brake the same. The cup-shaped member 46 65
is mounted upon the rod 45 and extends over
the projecting end of a tube 44 so that the
washer 47 bears against the wheel. A nut
51 holds the cup-shaped member 46 in place.

The inner ends of the rods 45 are angular, as 70
at 45^a. The angular ends of the rods 45 are

extended through slots 52^a formed in the 75
lower ends of levers 52. The upper ends of
the levers are forced apart by a longitudinally
extending rod or bar 53 having a wedge- 80
shaped rear end and mounted for longitu-
dinal movement on the wagon body. When
these rods 45 are drawn towards each other, 85
the cup-shaped members 46 draw the disk
wheels toward the disks of said brakes. 90
When the rods 45 are released the disk
wheels run free again. The object of the
cup-shaped members 46 is to give room for
the disk wheels to be forced against the
brake disks away from the ends of the tubes 95
44.

Any suitable means may be used for hold- 100
ing the rods 45 from rotation and it will be
seen that the angular ends 45^a of these rods,
extending through the levers 53, will hold 105
these rods from rotation with the wheel 48.
Any other means to this, however, may be
used. I have illustrated springs 54 which
urge the wheels away from the brake disks
50, but I have found in actual practice that 110
the springs 54 are not absolutely necessary in
the construction illustrated as the wheels will
run away from the brake disks unless the
brake disks are forced to the brakes. The
wheels will not run toward the brake disks 115
unless thrown against the same. It will be
noted that the wheel 48 is supported upon
the tubular member instead of being sup-
ported merely upon a rod as illustrated in
my pending application above referred to, as 120
the tubular member which constitutes an
axle section is not only stronger than the rod
itself, but is furthermore reinforced by the
rod extending through it.

I do not wish to be limited to the details 125
of construction except as defined in the ap-
pended claims.

I claim:—

1. A wagon including a hollow axle sec- 130
tion, a disk wheel mounted thereon and brak-
ing means comprising an annular brake disk
disposed concentric to the axle, and means
for shifting the wheel toward the brake disk.

2. In a wagon, hollow axle sections, disk 135
wheels mounted thereon, rods extending
through the axle sections and connected to
said wheels to shift them longitudinally with
relation to the axle sections, brake disks dis-
posed inward of the wheels and mounted
upon the axle sections, and means for shift- 140
ing said rods to shift the wheels against the
brake disks.

3. The combination with an axle and a disk wheel mounted loosely thereon, a brake member mounted upon the axle, and adapted to bear against the side face of the disk wheel, and means for drawing the disk wheel inward toward the braking member. 25
4. In a wagon, a hollow axle section, a disk wheel mounted upon the extremity thereof and rotatable therearound and shiftable 10 longitudinally upon the axle section, a rod extending through the axle section and having means on one extremity for engaging the disk wheel, the rod being longitudinally shiftable to shift the disk wheel inward, and 15 a brake disk operatively supported upon the axle section and against which the wheel is adapted to be shifted by said rod. 30
5. In a wagon, a hollow axle section, a disk wheel mounted upon the extremity thereof 20 and rotatable therearound and shiftable longitudinally upon the axle section, a rod extending through the axle section and having means on one extremity for engaging the disk wheel, the rod being longitudinally shiftable 35
- to shift the disk wheel inward, a brake disk 25 operatively supported upon the axle section and against which the wheel is adapted to be shifted by said rod, and resilient means urging the disk wheel away from the brake disk. 30
6. In a wagon a bolster, tubular members mounted upon said bolster and projecting beyond the same, disk wheels rotatably mounted upon the projecting ends of the tubular members and longitudinally shiftable thereon, rods extending through the tubular members and beyond the ends thereof, nuts mounted upon the extremities of the rods and operatively bearing against the exterior faces of the disk wheels, brake disks mounted upon the axle sections, one for each wheel, and manually operable means for shifting the rods toward each other to shift the wheels 40 into contact with the brake disks. 40

In testimony whereof I hereunto affix my 45
signature.

ERNEST S. SHOWERS.
